UNITED STATES PATENT OFFICE.

JAMES J. HORTON, OF ATTLEBOROUGH, MASSACHUSETTS.

DESIGN FOR A WATCH-CHAIN SWIVEL.

SPECIFICATION forming part of Design No. 13,444, dated November 21, 1882.

Application filed September 26, 1882. Term of patent 7 years.

To all whom it may concern:

Be it known that I, JAMES J. HORTON, of Attleborough, in the county of Bristol and State of Massachusetts, have invented a new and original Design for Watch-Chain Swivels; and I do hereby declare that the following specification, taken in connection with the accompanying drawings, forming a part of the same, is a full, clear, and exact description thereof.

10 My design consists in a watch-chain swivel having a neck or body with an oblong top, two opposite flat parallel sides, and two opposite converging convex sides, and provided with a bow or loop and a ring to enable the swivel 15 to be attached to the watch and to the chain, as will hereinafter appear.

Referring to the drawings, Figure 1 represents a swivel in perspective. Fig. 2 shows the neck or body in perspective as viewed 20 from opposite sides.

A represents the neck or body, which has an oblong top, two opposite flat parallel sides, a a' , and two opposite converging convex sides, a^2 a^3 . B is the bow or loop, and C is

the ring. The loop B and ring C may be of other shapes than those shown, the characteristic feature of the design being a swivel having a neck or body with an oblong top, two opposite flat parallel sides, a a' , and two opposite converging convex sides, a^2 a^3 . 25

What I claim, and desire to secure by Letters Patent, is—

1. The design for a watch-chain swivel, consisting of a neck or body having an oblong top, two opposite flat parallel sides, a a' , and two opposite converging convex sides, a^2 a^3 , 30 and provided with a bow and a ring, substantially as set forth.

2. The design for a watch-chain-swivel neck, consisting of a neck having an oblong top, two opposite flat parallel sides, a a' , and two opposite converging convex sides, a^2 a^3 , 35 substantially as described and shown.

JAMES J. HORTON.
